UNITED STATES PATENT OFFICE.

FRANKLIN E. MAINS, OF OROSI, CALIFORNIA.

STARTING-CRANK FOR AUTOMOBILES.

1,224,401.

Specification of Letters Patent.

Patented May 1, 1917.

Application filed November 18, 1916. Serial No. 132,135.

To all whom it may concern:

Be it known that I, FRANKLIN E. MAINS, a citizen of the United States, residing at Orosi, in the county of Tulare and State of California, have invented certain new and useful Improvements in Starting-Cranks for Automobiles, of which the following is a specification, reference being had to the accompanying drawings.

10 This invention relates to means for cranking automobiles or cranking the driving shafts of internal combustion engines and the general object of the invention is the provision of a cranking means so constructed as to avoid the danger of a reversal of the crank due to backfire, this reversal of the crank being very liable to break the operator's arm or otherwise injure it.

15 A further object of the invention is the provision of a very simple construction having few parts and these readily assembled, the device being so constructed that it may be readily adjusted to suit the resistance to cranking of any particular engine.

20 25 A further object of the invention is to provide a cranking device of this character in which the crank is held to the operating shaft by yielding means, the crank being held to the operating shaft in such manner 30 that the crank and the operating shaft will turn until they will rotate together when a steady impulse is given to the operating crank by the operator but wherein the crank and shaft will become disconnected when 35 any sudden impulse is delivered to the operating shaft and the operating shank is shifted quickly with relation to the crank.

40 Other objects will appear in the course of the following description.

45 My invention is illustrated in the accompanying drawings, wherein—

Figure 1 is an elevation partly in section of my improved safety crank;

Fig. 2 is a longitudinal sectional view 50 thereof; and

Fig. 3 is a face view of the disk 12, the lower end of the yoke and the roller 19.

55 Referring to these figures 10 designates the cranking shaft which is formed at its end 11 to provide a clutch adapted to operatively engage with the crank shaft of the engine. The nature of this clutch is not essential to my invention and may have any ordinary or usual form. Mounted upon the shank section 10 to rotate therewith is a disk 12 which at one point in its circumference is

formed with a longitudinal concave recess 13.

Loosely mounted upon the shaft section 10 is the crank arm which is designated generally 14 and is preferably formed in two sections which face toward each other. These sections are designated 15 and the sections are formed upon their margins with inwardly extending flanges 15^a which 60 abut against each other so that when the two sections are disposed in engagement a hollow arm is formed. The shaft 10 passes through the sections 15 adjacent one end thereof and the sections are disposed on each 65 side of the disk 12. The sections 15 are slotted at 15^a and operating in these slots is a yoke 17 carrying a transverse pin or axle 18 and mounted upon this axle 18 is a small wheel 19 having the same curvature 70 as the curvature of the concavity 13 into which this wheel is adapted to fit. The cross bar of the yoke 17 is widened as at 19^a and connected to the yoke is a longitudinally extending rod 20 which is rigidly attached to the yoke and extends between 75 the sections 15. Extending transversely through the crank 14 is a cross bar 21, the ends of which project out through slots formed in the end walls of the crank arm 80 14 and the rod 20 passes through an opening in this cross bar and disposed around the rod 20 is a coiled spring 22 which bears at one end against the cross bar 21 and at its other end bears against the yoke 17 and 85 particularly against the widened portion 17^a thereof. This spring, therefore, acts to force the rod 20 and the yoke 17 toward the disk 12 and force the wheel 19 into engagement with the recess 13 in the disk 12. 90 The walls of the crank arm 14 are formed with laterally projecting ears 23 through which pass adjusting screws 24 which engage with the laterally projecting portions of the cross bar 21 and it will be obvious 95 that by rotating these screws 24, the cross bar 21 may be engaged with the ears 23 and thus the yoke 17 adjusted. The sections 15 are connected to each other by screws 25 or any other suitable means and 100 a crank handle 26 is formed with a shoulder 27 and is screw threaded to engage with the sections 15 and assist in holding the two sections in abutting relation to each other. The inner ends of the sections 15 are formed 105 with abutting lugs 28 through which a bolt 29 passes. The operation of the invention 110

is obvious. The roller 19 may of course revolve freely around the disk 12 unless this roller 19 engages in the recess 13. Normally the roller 19 is held engaged in the 5 recess 13 by the spring 22, the tension of which may be regulated by the screws 24. The roller may, however, be forced out of its seat in the recess 13 against the force of the spring 22. When the crank is attached 10 to an automobile shaft, the spring 22 should be adjusted to such tension that by giving a quick steady pull on the crank the engine crank shaft may be turned against the compression in the cylinders. This tension of 15 the spring 22, however, should not be so great but that a quick jerk on the crank or a quick jerk on the shaft 10 will cause the roller 19 to rise out of the compression in the disk 23 and the disk 12, and the roller 20 19 will then roll completely around the disk 12 without turning the disk 12 or the shaft 10. It will thus be readily seen that when 25 the engine backfires, the roller 19 will rise out of the depression in the disk 12 and allow the shaft 10 and the disk 12 to turn backward without reversing the movement of the crank arm 14 and without any injury to the person who is doing the cranking.

While I have illustrated a certain form of 30 my invention which I believe to be particularly practical, and which has been found very effective for the purpose intended, it is obvious that the principle of the invention may be embodied in other forms and that 35 various modifications might be made without departing from the spirit of the invention.

What I claim is:

1. A starting crank for internal combustion engines comprising a shaft, a disk 40 mounted upon the shaft, the disk at one point in its periphery being formed with a concavity, a crank arm loosely mounted upon the shaft and housing the disk, a yoke 45 slidably mounted in the crank arm for longitudinal movement, a roller rotatably mounted in the yoke and having a curvature coinciding with the curvature of the concavity in the disk with which concavity the roller is adapted to engage, and a spring 50 urging the yoke toward the disk, the spring and yoke being housed within the crank arm.

2. A starting crank for internal combustion engines comprising a shaft, a disk 55 mounted upon the shaft, the disk at one point in its periphery being formed with a concavity, a crank arm loosely mounted upon the shaft and housing the disk, a yoke 60 slidably mounted in the crank arm for longitudinal movement, a roller rotatably

mounted in the yoke and having a curvature coinciding with the curvature of the concavity in the disk with which concavity the roller is adapted to engage, a spring urging 65 the yoke toward the disk, the spring and yoke being housed within the crank arm, and means whereby the tension of the spring may be adjusted.

3. A starting crank for internal combustion engines comprising a shaft, a disk mounted upon the shaft to rotate therewith and having a concavity in its periphery, a crank arm loosely mounted upon the shaft and comprising oppositely disposed sections 75 disposed on opposite faces of the disk, said sections being longitudinally slotted, a yoke slidably mounted in the slots of said sections and extending across the interior of the crank arm, a pin carried by the yoke, a 80 roller mounted upon the pin and fitting the concavity in said disk, a rod extending outward from the yoke, a cross bar slidably mounted in said sections and through which the rod passes, a spring surrounding the rod 85 and bearing at one end against the yoke and at the other end against said cross bar, and means mounted upon the crank arm for shifting the cross bar adjustably toward the yoke to thereby increase the tension of the 90 spring.

4. A starting crank for internal combustion engines comprising a shank formed at one end with a clutch adapted to engage the clutch on an engine crank shaft, a disk 95 mounted upon the first named shaft to rotate therewith, a crank arm formed in two opposed sections rotatably mounted upon the shaft on each side of the disk, a yoke slidably mounted in the sections of the crank 100 arm, a roller supported by the yoke and adapted to seat in the concavity of the disk, a rod extending from the yoke toward the free end of the crank arm, a cross bar slidably mounted in the yoke and through 105 which the rod passes, a spring surrounding the rod bearing at one end against the yoke and at the other end against the cross bar, oppositely projecting ears on the crank arm beyond the cross bar, adjusting screws passing through said ears and bearing against the cross bar, and a crank handle engaging the end of the crank arm and acting to hold the sections of the crank arm in engagement 110 with each other.

In testimony whereof I hereunto affix my signature in the presence of two witnesses.

FRANKLIN E. MAINS.
